UNITED STATES PATENT OFFICE.

DOMINICK DILEO AND NICOLA LALLI, OF UTICA, NEW YORK.

RADIATOR FOR LIQUID-COOLING SYSTEMS.

1,202,813.

Specification of Letters Patent. Patented Oct. 31, 1916.

Application filed February 13, 1915. Serial No. 8,027.

To all whom it may concern:

Be it known that we, DOMINICK DILEO and NICOLA LALLI, citizens of the United States, residing at Utica, in the county of Oneida and State of New York, have invented new and useful Improvements in Radiators for Liquid-Cooling Systems, of which the following is a specification.

This invention relates to radiators for liquid-cooling systems, the main object of the invention being to produce a radiator which may be economically repaired in case a leak springs therein in one of the liquid conduits or tubes, the construction of the radiator being such that the radiation plates or flanges may be readily disconnected in any desired number from the liquid tubes, thereby exposing a sufficient portion of one or more tubes to enable the leak to be repaired and stopped. This enables the radiator to be repaired by an unskilled workman and at almost any place such as a small village or even on the road, a soldering iron and a small amount of solder being all that is required in addition to some kind of a burner or lamp for heating the soldering iron.

With the above and other objects in view, the invention consists in the novel construction, combination and arrangement of parts, as herein described, illustrated and claimed.

In the accompanying drawings, Figure 1 is a front elevation of a radiator embodying the present invention, the outside casing being partly broken away. Fig. 2 is a horizontal cross section through the same illustrating by dotted lines the manner of withdrawing the radiation plates. Fig. 3 is a vertical cross section through a portion of the radiator on an enlarged scale. Fig. 4 is a fragmentary vertical section through the radiator showing the provision of a space for one of the clamping bolts or screws. Fig. 5 is an enlarged fragmentary vertical section showing the disposition of several radiation plates in relation to one or more of the liquid tubes. Fig. 6 is a detail perspective view showing one of the radiation plates. Fig. 7 is a similar view of another adjoining radiation plate.

In the main the radiator resembles that now in common use on automobiles, motor trucks and the like, the same being shown as comprising the upper manifold or water chamber 1, the lower water chamber or manifold 2, and water pipes 3 connected at

their upper and lower ends respectively to the manifolds 1 and 2 so as to conduct the water from one manifold to the other.

As shown in Fig. 2, the tubes 3 are all arranged parallel to each other and are further arranged in rows or series, said rows or series being parallel to each other. Any desired number of rows of pipes may, of course, be employed in accordance with the size and capacity of the radiator and also any desired number of pipes may be contained in each row, the essential feature of the invention being that said pipes are arranged in parallel series substantially as shown in Fig. 2.

In connection with the pipes arranged as hereinabove set forth, we employ two series, A and B, of radiation plates or, as they are sometimes termed, radiation fins or flanges. The shape of each one of these radiation plates is illustrated in Figs. 2, 5 and 6 wherein it will be observed that said plate is provided with a longitudinal series of slots 4 each of said slots being open at one end so that the plate may be slid inwardly to straddle the water pipes of the adjacent rows as clearly indicated in Fig. 2. Some of these plates are inserted from the front of the radiator and the remainder are inserted from the rear of the radiator, and they are removed from the radiator in the same manner. Preferably, each plate is in the form of an elongated rectangular thin sheet of metal and the slots 4 are formed by a suitable punching press which simultaneously produces all of the slots in each radiation plate. Flanges 5 and 6 extending longitudinally of the side edges of the slots are pressed downwardly and said flanges converge toward each other as shown in the drawings. Therefore, when the radiation plate is pushed inwardly to its final position, the flanges 5 and 6 engage and press frictionally and with a spring action against the pipes at points diametrically opposite thereof. This provides for heat radiating contact between the radiation plates and the pipes and also avoids any possibility of said plates rattling or jarring loose.

C designates an outer shell or casing which is adapted to slide over the structure hereinabove particularly described and as indicated in Figs. 1 and 2, said casing C being preferably removable by lifting the same in a vertical direction off the top of the structure hereinabove described. In order

to hold all of the parts securely together, we employ a suitable number of screws or bolts 7 which are inserted through holes in the outer casing or shell C as shown in Fig. 5 1 and which pass between certain radiation plates adjacent to the upright side frame members 8 of the radiator which connect the top and bottom manifolds 1 and 2 and which, incidentally, are provided with off-standing arms 9 by means of which the radiator may be supported on a part of the frame of the machine. In order to provide sufficient space for each of the bolts 7, one of the plates, as shown in Fig. 4, has its opposite end portions split or divided, one part thereof being turned upwardly and the other downwardly to form terminal spacing flanges or members 10. By reference to Fig. 4 it will be observed that every other plate is provided at the ends or the extremities thereof with upwardly and downwardly inclined or obliquely disposed spacing flanges or members, the same bearing against the other plates so as to hold all of the plates in spaced relation to each other while at the same time leaving spaces for the clamping bolts 7. At the rear of the radiator there are strips or plates 11 through which the screws or bolts 7 pass, the latter being held by nuts 12.

From the foregoing description taken in connection with the accompanying drawings, it will now be understood that it is a comparatively simple and easy matter to repair a leak in the radiator. The operator first removes the outer shell or casing C. He

then locates the leak by close observation and thereafter removes a sufficient number of radiation plates to expose that portion of the pipe 3 to enable the hole or leak 40 therein to be soldered. If one of the forward pipes is affected, it is not necessary to remove any of the plates of the rear series A and conversely, if one of the pipes 3 of the rear rows is affected. After the 45 leak has been soldered or otherwise repaired, the removed radiation plates are reinserted and the casing C replaced and secured.

What we claim is:—

In a radiator for liquid cooling systems, 50 the combination of parallel liquid tubes arranged in parallel series, and radiator plates extending at right angles to said tubes and in parallel and spaced relation to each other, said radiator plates being formed with tube 55 receiving slots each open at one end permitting said plates to slide into and out of position and normal relation to said tubes, said radiation plates being provided at opposite sides of each slot with downwardly converging yieldable flanges bearing against said tubes, alternate plates being formed with spacing flanges which are normally disposed at oblique angles to the bodies of the plates. 60

In testimony whereof we affix our signatures in presence of two witnesses.

DOMINICK DILEO.
NICOLA LALLI.
